[57] **ABSTRACT**

An improved self-healing electrolytic transistor using electrode materials and solutions similar to those used in electrolytic capacitors; in which, the collector is placed within the emitter to base current path; also having means for varying the internal input resistance; and which is capable of high power output.

ELECTROLYTIC TRANSISTOR WITH COLLECTOR IN BASE-EMITTER CURRENT PATH

GENERAL DESCRIPTION OF INVENTION

The objectives of this invention are:

1. To increase the power dissipation ability as compared to the solid state devices in the present state of the art.
2. To secure a greater power amplifying ability than present solid state devices in the art.
3. To achieve a better manufacturing control of electrical characteristics than the transistors in use at the present time.
4. To achieve a lower cost of production than the present types of semiconductor devices.

This device is an electrolytic transistor with three (or more) electrodes in contact with an electrolytic solution and which can be used to amplify DC and AC currents of various magnitudes and frequencies depending on the material, size and spacing of the electrodes; the composition and quantity of the electrolyte; and the formation voltage of the film on the surface of the emitter and collector.

Except for necessary changes in operating voltages and the electrical values of some components it can be used in circuits identical to those used with many transistors. The major difference between this electrolytic transistor and other electrolytic transistor devices is the means used for controlling the collector current and varying its input resistance.

Instead of causing the control current to flow along the side of the collector the control electrode is placed in such a position as to cause the control current to flow through passages in the collector electrode, thus resulting in a greater transfer current from the emitter to the collector. Since the base, or control electrode, is mounted on the side of the collector opposite to the emitter there is a greater resistance to the flow of emitter to base current thus resulting in a greater emitter base input resistance which is an advantage when this device is connected to circuits where less loading is desired.

A specific embodiment of this device as power amplifier transistor is as follows:

Referring to the diagram:

Item 1, the emitter, is a circular disc of aluminum four inches in diameter by one-half inch thick. The surface of this emitter electrode is coated with a film of aluminum oxide (Al_2O_3) preformed in a solution of 10 percent boric acid (H_3BO_3) by weight and 90 percent distilled water (H_2O) by weight and preformed by the application of a DC voltage (positive polarity on electrode, negative polarity on solution) gradually increased up to 50 volts. A hole one-eighth inch in diameter is drilled at the center of the disc and perpendicular to the surface of the emitter electrode for the purpose of injecting the electrolyte after assembly of this device.

External emitter connection, item 7, made by means of a 14 gauge copper wire fastened to the edge of the disc.

Item 2, the collector, is the same as item 1 except that, prior to the preformation process, twenty one-sixteenth inch holes are drilled equally spaced in a circle 1 inch in radius from the center of the disc and perpendicular to its surface.

No filling hole is needed. All surfaces of the collector are preformed in the same manner as the emitter except that the preformation voltage is increased to 500 volts. External collector connection, item 8, is made in the same manner as item 7.

Item 3, the base, is the same as item 1 except that no preformation of its surface is needed as no film is desired on the base electrode. External base connection, item 9, is made in the same manner as item 7.

Items 4 and 5 are identical insulating spacers consisting of rubber rings one-fourth inch thick and with an inside diameter of 3 inches and an outside diameter of 4 inches.

All items are assembled in the order indicated in the diagram. The rubber washers are cemented to the adjacent electrodes by means of a waterproof rubber-to-metal cement.

The assembly is then clamped in a vise until a strong leak proof bond results.

After the cement has hardened; the cavities, item 6, in the device are filled with the same solution as was used during preformation. (Allowance must be made for expansion of the liquid during operation.) Then the two filling holes are filled with rubber cement to prevent leakage of the electrolyte.

A DC voltage of 50 volts is applied between emitter and base (in order to again preform the oxide film on the emitter) with the positive potential on the emitter; and then a voltage of 500 volts is applied between the collector and the base with the positive potential on the collector.

Thick electrodes and a large quantity of electrolyte are used in order to maintain a lower temperature in this power device.

While this specific embodiment is intended for use in an audio amplifier it may be constructed for low power or high frequency use by using components of smaller dimensions and the use of other electrolytes that form thicker oxide films, (such as, oxalic, sulphuric, and chromic acids and their salts). This results in a reduction in capacitance between the electrodes and increases the cut off frequency of the device.

OPERATION OF THE DEVICE

This device is an improved electrolytic transistor designed to amplify DC and AC currents and operates in a manner very similar to an NPN semiconductor type transistor. Aluminum oxide films are used instead of the barrier junctions used in semiconductor transistors (tungsten, cadmium, or other oxide films may also be used).

The emitter is biased negative with respect to the collector and the base is biased positive with respect to the emitter. This results in a very high resistance from collector to emitter and from collector to base (reversed bias), and a very much lower resistance from emitter to base (forward bias). The base electrode has no film on it and the voltage applied between the base (positive) and the emitter (negative) is kept below the point at which a film will form on the base (2 volts). If a higher input voltage is desired the base may be plated with a material resistive to oxidization such as gold, chromium etc.

The solution (10 percent boric acid and 90 percent distilled water) is used as a means for applying the volt-

ages to the electrodes (internally); to provide a conductive path for the current from the emitter through the holes in the collector to the base; and from the emitter to the collector, and also as a means for reducing internal heat. The emitter-base current flows through small holes in the collector in a very close proximity to the collector's high resistance film. If the emitter-base current is varied by an input signal it varies the resistance of the collector film causing a much greater variation in the emitter-collector current in the collector-emitter (JT) circuit. By decreasing the diameter of the holes in the collector and/or by increasing the thickness of the film on the collector (by applying higher voltages during formation of the film or during operation of this device) the restriction to the flow of emitter base current through the solution will be increased, resulting in a higher input resistance between the emitter and base and also a greater effect of the emitter-base current on the emitter-collector current. This device may be used in circuits similar to NPN transistor circuits and may be used as a substitute for an NPN transistor provided proper operating voltages are applied.

It is particularly adapted for use as an audio power output electrolytic transistor.

The collector film may be preformed up to a voltage of 800 volts and this device may be operated with maximum surge voltages near that amount. An advantage of this transistor over the semiconductor type is that this transistor is self healing when overloads or transient surges occur; due to the reforming qualities of the film on the electrodes.

Another advantage of this device is that, due to the cooling effect of the electrolyte, it has an increased heat dissipating ability.

DESCRIPTION OF DRAWING

While this drawing shows the use of circular rings and discs, the transistor can be manufactured in various configuration (such as rectangular or tubular). The FIGURE is a cross sectional view of the electrolytic transistor:

1. Emitter, consisting of an electrically conductive disc coated (on its internal surface) by a material offering non linear electrical current conduction. This film may be formed by electrical, chemical, heat process.

2. All surfaces, external and internal, are coated with

a film having non linear electrical conduction properties. This film may be formed chemically, electrically, or by heat process.

3. Base, consisting of an electrically conductive disc. 5. No film is necessary.

4. Insulating ring used as separator between collector and base.

5. Insulating ring used as separator between collector and base.

10. 6. Liquid or paste electrolyte between emitter, collector, and base, and in the holes prefabricated in the collector.

7. Emitter connection.

8. Collector connection.

9. Base connection.

I claim:

1. An electrolytic transistor comprising three electrically conductive electrodes spaced from each other with the side electrodes forming the base and emitter of the transistor and the central electrode the collector thereof, electrically insulating gasket-like members having central openings therein interleaved and sealed between the electrodes and together with the electrodes forming a pair of electrolyte containing spaces between the electrodes, the emitter and collector of said electrodes being composed of film-forming metal and the collector having passages therethrough interconnecting said spaces, a film-forming electrolyte contained in said spaces and extending through the passages in the collector electrode, said emitter and collector electrodes having conduction films on the surfaces thereof contacting the electrolyte, said films being non linear in conduction of electrical current as to direction from said electrolyte to electrode in comparison to electrical current from electrode to electrolyte.

20. 25. 2. An electrolytic transistor as recited in claim 1 wherein said collector and emitter electrodes are aluminum.

3. An electrolytic transistor as recited in claim 1 wherein said electrolyte is a liquid solution.

4. An electrolytic transistor as recited in claim 1 wherein said base electrode is nonfilm-forming in said transistor.

30. 35. 5. An electrolytic transistor as recited in claim 1 wherein said electrodes have terminals for electrical connections thereto.
